UNITED STATES PATENT OFFICE.

ORA DEARBORN SHAW, OF BOSTON, MASSACHUSETTS.

DESIGN FOR A CAP.

No. 38,125.

Specification for Design.

Patented July 3, 1906.

Application filed April 15, 1905. Serial No. 255,852. Term of patent 14 years.

To all whom it may concern:

Be it known that I, ORA DEARBORN SHAW, a citizen of the United States, residing at Boston, Suffolk county, Massachusetts, have invented a new, original, and ornamental Design for Caps, of which the following is a specification, reference being had to the accompanying drawing, forming part thereof.

The figure is a front view of the cap, showing my new design.

I claim—

The ornamental design for a cap, as shown.
ORA DEARBORN SHAW.
